LATCHING MEANS

Marvin Lyle Thomas, Norfolk, Va.

Application February 13, 1939, Serial No. 256,215

3 Claims. (Cl. 217—60)

This invention relates to latches, and more particularly to quick releasable latching means of the type having a pin movable within a slot and engageable within a reentrant recess.

The type of latch to which this invention relates has been extensively used in the past, and one such use of considerable importance involves the fixing of a pin to the body portion of a compartment structure and a flat hinged member to the cover for the compartment, the hinged member being provided with a reentrant recess for the reception of the pin whereby the cover may be secured in opened position and yet may be readily closed.

Heretofore, it has been customary to employ latches of the type indicated for various purposes and such latches have had wide application to many arts. As the type of latch under consideration was first employed, it was necessary in order to release the same that the hinged member be manually swung out of engagement with the pin so that it could be moved. Thereafter, as the art developed, many attempts were made to provide an automatic disengaging means for variously directing the relative movements of the pin and the reentrant recess and while certain of these improved constructions were quite satisfactory, they have not been completely successful largely because of the complexity of the apparatus required to accomplish the desired result.

This invention has for an object the provision of a simplified latching means which overcomes the mechanical and structural difficulties heretofore encountered in the art and at the same time contemplates the provision of means for disengaging the pin and reentrant recess without the necessity of touching the member having therein such recess. The present invention involves the provision of a reentrant recess in a movable member and by movement of such member in a single direction, the pin will come to rest adjacent the reentrant recess. Movement in the opposite direction will then cause the pin to be guided into the recess and be held therein. Returning to the first type of movement, the pin may be disengaged from the recess, and returning to the second type of movement, the member having therein the recess may then travel back to its original position, means being provided to cause it to pass over the pin. The object is to provide an automatic disengaging means of the type outlined above which contemplates a spring adjacent the reentrant recess and so positioned as to guide the pin therein when desired and when

the pin and recess are to be disengaged, the spring will function to prevent the recess from receiving the pin.

This invention has an important application in the art relating to lid supports adapted for use on automobile hoods, automobile luggage compartments, trunks, cabinets, desks and the like having hinged covers and in this connection the present invention involves the provision of a support pivotally connected to a cover and having a longitudinally extending slot therein adapted to cooperate with a pin held by the side wall of the closure proper. Near the end of this slot, remote from the end adjacent the pivot point, 10 there is provided a reentrant recess adjacent which there is positioned means for permitting said recess to receive the pin when desired, or if desired preventing the recess from receiving therein the pin. In a modification of the present invention, instead of a slotted support, it is possible to have either a slot or guiding means provided in the side wall of the container for the purpose of receiving the lid support member containing the latching means constituting the present invention.

Other objects and advantages of the present invention will be apparent from a consideration of the following detailed description when taken in conjunction with the annexed drawing wherein:

Figure 1 is a side elevation partially cut away showing an adaptation of the present invention to hinged covers, the cover being shown in opened position;

Figure 2 is an end elevation partially cut away showing the construction of Figure 1;

Figure 3 is a side elevation partially cut away showing the position of the support with respect to the cooperating pin when the cover is closed;

Figure 4 is a detailed view of the various positions assumed by the guide spring as the cover is lowered;

Figure 5 is a detailed view of a modification of the invention dispensing with the slot in the support; and

Figure 6 is a section taken along the line 6—6 of Figure 5.

Referring to the drawing in detail, and more particularly to Figures 1 to 4 inclusive thereof, there is shown a cabinet or box 10 provided with a cover 11 adapted to move into various angular positions with respect to the top of the cabinet 10 by virtue of hinged connection 12. Suitably secured to the top 11, is an L-member 13 adapted

to receive therein a pin 14 which constitutes a pivot support for the arm 15.

Arm 15 is centrally slotted for most of the length thereof, and adjacent the end remote from the pivot 14 there is a reentrant recess 16 near the mouth of which is fastened a leaf spring 17 spot-welded to the arm 15 at 18. It should be noted that the spring member extends beyond the mouth of the reentrant recess out into the longitudinally slotted portion of the arm generally transverse the same. Beyond the spring 17 the longitudinal slot extends for a short distance terminating at 20.

Mounted on the side wall of the cabinet 10, there is a pin 19 which is received in the slotted portion of the arm 15 and constitutes a guide for said arm in its pivotal movement about the point 14. When the cabinet is closed the position of the pin is that shown in Figure 3. As the top 11 is raised that portion of the arm 15 having cut therein the reentrant recess 16 will approach the pin 19. As the top is moved upwardly about its axis at the hinge 12, the pin 19 will eventually contact the spring 17. At this point, if the lifting action on the top 11 is stopped and the top is released, the reentrant recess 16 will receive the pin 19 therein. Thus, it will be seen that the top will be supported in open position as shown in Figure 1.

When it is desired to move the top from the position shown in Figure 1 to that shown in Figure 3, it is only necessary to raise up the top a bit further than the position of Figure 1 causing the spring to be flexed in the direction away from the pivot point 14 to release the pin 19 from the slot 16. The pin will then be received by the end of the slot designated at 20 as shown in Figure 4. Thereafter releasing all upward force tending to open the lid 11, gravity will cause the same to fall forcing the arm 15 downwardly. As this is done the pin 19 will be struck by the spring 17 again, this time causing it to flex toward the pivot point 13 effectively closing the reentrant recess 16 and permitting the arm to move downwardly, guided by the pin 19 until it reaches the position shown in Figure 3. By the construction illustrated, it will be seen that the spring 17 has a dual function. First, when it is desired to place the pin 19 within the reentrant recess 16, the spring acts as a guide; then when it is desired to disengage the pin from the reentrant recess and close the top, the spring 17 will effectively shut off the reentrant recess so that the arm 15 may move into the position assumed when the lid is closed.

The spring 17 shown in Figures 1 to 4 inclusive is generally L-shaped in cross-section along the base portion of its length so that the flexing portion may be inserted into a slot cut in the arm 15 and a flat portion 21 will overlie said arm. At this flat portion, the spring is spot-welded, riveted or otherwise suitably secured in position as shown at 18.

The construction shown in Figures 5 to 6 of the drawing involves the provision of a slot defined by staple 22 which is suitably secured to the side wall of the cabinet or box 10. By this expedient, the longitudinal slot in the arm 15 shown in Figures 1 to 4 inclusive can be obviated since the arm may be guided by the member 22. The arm designated as 23 pivots about a point 24 which may be attached to the top of a cabinet or box in the manner shown in Figure 1 and the arm 23 as a whole is received by the staple or guide-member 22. A reentrant recess 25 is provided

near the lower end of the support arm 23. Adjacent the entrance to the reentrant recess there is a spring 26 similar in construction to spring 17 and mounted in a similar manner. Opposite the spring 26 there is another recess 27 which functions to receive the pin after it has been disengaged from reentrant recess 26 and prior to the lowering of the lid or top which will result in the movement of the arm 23 toward the position assumed when the top is closed.

In operation, the device shown in Figures 5 and 6 is similar to the device shown in Figures 1 to 3 inclusive. When the top is open, a portion of the member 22 will be received into the reentrant recess 25 and will constitute a support point for the weight of the cabinet top. When it is desired to lower the top, it is first slightly raised so that the spring will be flexed away from the point 24 permitting the member 23 to engage the staple 22 at point 27. Thereafter, the lid is lowered flexing spring 26 toward point 24 and permitting the arm 23 to assume non-supporting position.

I claim:

1. In combination with a closure having a fixed pin thereon and hinged cover, a longitudinally slotted arm pivotally connected to the cover and having in communication with said slot a reentrant recess adapted to receive said pin, and a leaf spring attached to said arm and projecting from the side thereof having the recess therein, said leaf spring being mounted adjacent the mouth of said recess and extending out from said arm at a point between said recess and the terminus of the slot adjacent the free end of the arm into the said slot transverse the longitudinal axis thereof for a distance about one-half the width of said slot, said leaf spring being adapted to be flexed across the mouth of said recess, whereby the pin may be disengaged from the reentrant recess by movement of the cover away from the closure and when the cover is released the spring will be flexed by the pin to close the mouth of the recess.

2. In combination with a closure having a fixed staple thereon and a hinged cover, an arm pivotally connected at one end to the cover and having in one side thereof a reentrant recess adapted to receive one shank of said staple, the mouth of said reentrant recess opening toward the free end 45 of said arm, and a leaf spring attached to said arm on the side thereof having the reentrant recess therein, said leaf spring having its free end projecting from said side of said arm at a point adjacent the mouth of said recess and between 50 the mouth of said recess and the free end of said arm, said leaf spring projecting for a distance sufficient to bridge said mouth when flexed thereacross, stop means on said arm cooperating with said shank of said staple to limit the movement of said arm in one direction, said staple bridging said arm to guide the same with respect to said shank thereof.

3. A latch adapted to function as a tie for relatively reciprocal elements comprising, a member secured at one end to one of the elements and a stud secured to the other element, said member having a stud contacting edge defining a path of relative movement of said stud and said member, means for continuously maintaining said stud and member in said path regardless of the direction of relative movement, said edge of said member being provided with a reentrant recess, and an element attached to said member normally projecting from said edge into said path at a point adjacent said recess and between the

recess and the free end of said member, said element being spring held in normal position but adapted to be moved in either direction by contact with said stud, said element being so positioned with respect to the recess as to act as a groove when moved in one direction and when moved in the other direction serving to bridge the mouth of said recess to prevent entry of said stud

therein, whereby said element may aid in directing the stud into the recess upon relative movement of said stud and member in one direction and will be flexed by contacting with said stud to close the recess upon relative movement in the opposite direction after relative movement beyond the recess.

MARVIN LYLE THOMAS.
